Primary Examiner — Jack Reickel*Assistant Examiner* — Michael A Kervin(74) *Attorney, Agent, or Firm* — Ware, Fressola, Maguire & Barber LLP(57) **CLAIM**

The ornamental design for a conduit nipple grounding bushing, as shown and described.

DESCRIPTION

FIG. 1 is a front perspective view of the conduit nipple grounding bushing, showing my new design.

FIG. 2 is a front view thereof.

FIG. 3 is a rear view thereof.

FIG. 4 is a right side view thereof.

FIG. 5 is a top view thereof.

FIG. 6 is a left side view thereof; and,

FIG. 7 is a perspective view thereof, shown with environment.

The dashed lines shown in FIG. 7 are for the purpose of illustrating a grounding lug attached to the conduit nipple grounding bushing that form no part of the claimed design.

1 Claim, 6 Drawing Sheets(56)
